(57) **CLAIM**

The ornamental design for a electric bicycle frame as shown and described.

DESCRIPTION

FIG. 1 is a perspective view of an electric bicycle frame showing the claimed design.

FIG. 2 is a front elevational view thereof;

FIG. 3 is a rear elevational view thereof;

FIG. 4 is a top plan view thereof;

FIG. 5 is a bottom plan view thereof;

FIG. 6 is a right side view thereof; and,

FIG. 7 is a left side view thereof.

The broken lines depict portions of the electric bicycle frame that form no part of the claimed design.
